CARBURETOR MUFFLER

Guy M. Hartsock, South Bend, Ind., assignor, by
mesne assignments, to C. F. Burgess Laboratories,
Inc., Chicago, Ill., a corporation of Delaware

Application August 24, 1929, Serial No. 388,113

2 Claims. (Cl. 181—50)

This invention relates to mufflers for carburetors and has for its object to provide muffling means therefor including an acoustic material to eliminate the various noises heretofore present in carburetors.

A further object is to provide a muffler having an outer shell enclosing a relatively thick layer of acoustic material supported by a screen secured to the shell.

10 A still further object is to provide a flange adapted to be connected with the air intake of a carburetor, a casing or shell secured to projections on the flange to permit free passage of air around the periphery of the flange into the carburetor, and a lining in the shell composed of acoustic material to break up the air currents as the air passed into the carburetor to thus eliminate the objectionable noises commonly present.

These being among the objects of the present 20 invention, the same consists of certain features of construction and combination of parts to be hereinafter described with reference to the accompanying drawing, and then claimed, having the above and other objects in view.

25 In the accompanying drawing which illustrates a suitable embodiment of the present invention,

Figure 1 is a fragmentary side elevational view of an engine provided with an intake manifold to which is attached a carburetor having my invention included thereon.

Figure 2 is an enlarged side elevation of the muffler, a part of the same being broken away to more clearly show the invention.

Figure 3 is a bottom plan view of the muffler.

30 Figure 4 is a section taken on the line 4—4 of Figure 3.

For the purpose of illustration, I have shown the muffler as attached to a down draft carburetor and while my invention finds great utility 40 when used in connection with a carburetor of that design, it is to be understood that it is not limited to use with any particular design of carburetor but that it may be used with great efficiency with many of the designs of carburetors now on the market.

Referring to the accompanying drawing in which like numerals refer to like parts throughout the several views, I have shown an internal construction 45 engine 10 having an intake manifold 11 attached thereto. The manifold 11 is provided with a flange 12 to which is attached a carburetor 13 by means of the bolts 14. The construction just described may be of conventional design 50 and in itself forms no part of my invention, ex-

cept in so far as the same is used in connection with a muffler about to be described.

The muffler comprises a supporting or base member 15 terminating in a flange 16 which is split at 17 and has a pair of projecting ears 18 5 adjacent to the split 17. The flange 16 is adapted to be attached to the air intake of the carburetor 13 and is secured thereon by means of the bolt 19 threaded into the projections 18 to securely clamp the flange 16 on to the air intake. The member 10 15 is preferably provided with a rolled edge 20 on which are provided projecting lugs 21.

A dome-shaped shell or casing 22 has its free edges extending around the member 15 and is attached to the lugs 21 by means of the screws 23 15 so as to permit free passage of air into the carburetor 13 around the periphery of the member 15. A lining 24 is provided within the shell 22 and comprises a non-inflammable acoustic material preferably made of steel wool, however, other materials such as copper or brass wool, asbestos or a fibrous, spongy or porous mass may be substituted. The lining 24 is secured within the shell 22 by means of the supporting member 25 which may be formed of screen, perforated metal or 20 other non-inflammable material formed with openings therein permitting the lining to be effective to deaden the noises caused by the air currents passing into the carburetor.

The shell 22 is spaced from the rolled edge 20 30 of the member 15 to permit an unobstructed passage of the air currents around the periphery of the edge 20 into the carburetor. As the air passes into the carburetor around the member 15, the air currents will be broken up, the lining 25 acting as a sound absorbing means because of its properties as an acoustic material to deaden the noises now common in carburetors due to the in-rushing of air currents when the throttle is 35 opened.

40 From the foregoing description it will be apparent that I have provided a means for eliminating the noises now common in carburetors and also have provided means for obstructing particles of dirt and foreign matter from entering the 45 carburetor because of the fact that such foreign particles will impinge against the screen 25 and will be sucked into the carburetor and cause damage to the same.

From the foregoing description it will be apparent that the present invention provides a very satisfactory means for correcting a condition now present in carburetors by providing a muffler for the same and that formal changes may be made 50 in the specific embodiment of the invention de- 55

scribed without departing from the spirit and substance of the broad invention, the scope of which is commensurate with the appended claims.

What I claim is:

- 5 1. A silencer for use with the air inlet conduit of an internal combustion engine carburetor comprising a tube-like element to be attached to the air intake pipe of the carburetor, the outer end of said tube-like element being provided with a curved outwardly extending flange, spaced lugs formed on the curved part of said flange, a dome-shaped member secured to said lugs to provide a space between said flange and said dome-shaped member for the passage of air into said intake 10 pipe, and a layer of sound-absorbing material arranged on the interior of said dome-shaped member.
- 15

2. A silencer for use with the air inlet conduit of an internal combustion engine carburetor comprising a tube-like element to be attached to the air intake pipe of the carburetor, the outer end of said tube-like element being provided with a curved outwardly extending flange, spaced lugs formed on the curved part of said flange, a dome-shaped member secured to said lugs to provide a space between said flange and said dome-shaped member for the passage of air into said intake 10 pipe, a layer of sound-absorbing material arranged on the interior of said dome-shaped member, and a non-flammable pervious covering for said sound-absorbing material.
